UNITED STATES PATENT OFFICE.

JOSEPH PRICE, OF NEW YORK, N. Y., ASSIGNOR TO THE GRISCOM RUSSELL COMPANY,
OF NEW YORK, N. Y., A CORPORATION OF DELAWARE.

AIR COOLER.

Application filed July 8, 1921. Serial No. 483,355.

To all whom it may concern:

Be it known that I, JOSEPH PRICE, a citizen of the United States, residing at No. 2550 Briggs Avenue, New York city, in 5 the county of Bronx, State of New York, have invented certain new and useful Improvements in Air Coolers; and I do hereby declare the following to be a full, clear, and exact description of the invention, such 10 as will enable others skilled in the art to which it appertains, to make and use the same.

The present invention relates to an apparatus for transferring heat between two 15 fluid mediums, and is particularly applicable as a heater or cooler for air or other medium which approximately obeys the laws of a perfect gas.

Air dryers, ventilators, and the like are 20 widely used at present in industrial operations. In such apparatus it is ordinarily desirable that the air utilized be clean and dry and, since the atmosphere in the proximity of such apparatus is ordinarily moisture laden and full of dust and other impurities, it is common to pass the air 25 through the apparatus in a closed circuit, thus repeatedly utilizing the same air and supplying only enough additional air to 30 compensate for the leakage and various losses occurring in the apparatus. The temperature of the air is changed as it passes through the ventilator or other apparatus, and it is necessary that means be provided in the circuit to restore the volume of 35 the gas to its original temperature before again passing it to the apparatus. For instance, the ventilating systems employed in connection with large electrical genera- 40 tors and motors such as used on electrically propelled ships and in various industrial plants handle enormous volumes of cooling air and, since dust and dirt accumulated in the windings of these machines would be 45 damaging, it is desirable that the ventilating air be passed in a closed circuit with a cooling device placed at some point in the circuit. The ventilating air issuing from electrical machinery of this type may be at 50 a temperature of 60° C., and a cooling device must be provided which is capable of receiving the air at this high temperature and at the high velocity with which it issues and cool it to a materially lower tem- 55

Heretofore apparatus of this type commonly consisted of tubes for containing the working fluid and a surrounding air passage, the tubes usually extending between the two tube sheets into which they are expanded or made tight by means of packed ferrules. The transfer of heat by conduction in a gas is slow, and for efficient heating or cooling of such a medium it is necessary that the gas be brought repeatedly 60 into intimate contact with the heat transferring surfaces. Even the heat transfer rate for gas is low and consequently extensive cooling surfaces are required. In order to provide extensive cooling surfaces within 70 a small space it has been proposed to use tubes for the working fluid which are fluted, finned, or otherwise designed to present a large heat transferring surface. Such a tube construction has not proven satisfactory 75 when used with the usual design above described due to the difficulty of replacing a damaged tube. When finned tubes are employed a single tube cannot be removed by sliding it through the holes in the tube 80 sheets as can be done with straight tubes of ordinary design. To remove a finned tube it is necessary that one tube sheet be completely removed from all the tubes if the 85 unit is of the common design above described.

It is accordingly an object of the invention to provide an apparatus of this type of small dimensions, having an extensive heat transferring surface, and having heat transferring elements which are independently removable, thus simplifying and making less expensive the necessary repair and maintenance work.

It is a further object of the invention to 95 provide an apparatus of this type adapted to be built in any capacity and which may be readily designed to efficiently handle large volumes of gas at high velocities, the gas being brought repeatedly into contact 100 with the heat transferring surface.

It is also an object to provide a device of 105 this character in which the working fluid is both admitted and discharged at one end of the shell, the water head being constructed either to admit discharge liquid at the same side of the head or at opposite sides, depending on the condition of the particular installation.

I have illustrated a preferred embodiment.

ment of my invention in the accompanying drawings, in which

Figure 1 is a sectional elevation through an air cooler embodying my invention;

5 Fig. 2 is an end view;

Fig. 3 is a top view partly in section;

Fig. 4 is a plan view of the bottom head;

Fig. 5 is a sectional view taken on the line 5—5 of Fig. 4;

10 Fig. 6 is a view showing the type of tube construction employed; and

Figs. 7 and 8 are detail views showing modified forms of bottom head; and

15 Figs. 9 and 10 illustrate a modified form of water head adapted for multi-pass construction.

Referring to the drawings, particularly to Figs. 1 to 3, 1 indicates the shell of the apparatus, shown here as a metallic container 20 of rectangular section which may either be cast or made from sheet metal. The shell 1 is provided at its ends with flanges 2 and 2^a which may be cast integrally with the shell or formed by angle irons riveted to 25 the ends of the shell. A rectangular inlet 3 for the air and a similar outlet 4 are provided in the narrower sides of the shell. These are substantially equal in area to the sides of the shell and are provided with 30 flanges 5 for attachment in series with the other members included in the air circuit.

Within the shell there is positioned a plurality of longitudinal tubes 6 having their lower ends expanded into a tube sheet 7 which fits against the lower flange 2 and serves as a support for the tubes. The upper ends of the tubes are not secured in a tube sheet as are the lower ends but are left unsupported, and individual cap members 8 35 of inverted U-shape are expanded, screwed or otherwise suitably fastened over the free ends of adjacent tubes, thus grouping the entire body of tubes into a number of independent elements each containing a pair of tubes. Each of the members 8 contains a tubular passage executing a 180° turn and serves as means for connecting the two tubes of the elements in series, the fluid passing up one of the tubes and down the other.

50 The lower or open ends of the tubes open into a head 9, best shown in Figs. 4 and 5. This head is a metal casting comprising an inlet 10 for admitting the working fluid into a passage 11 extending the length of the head, and an outlet 12 through which the fluid is discharged from a longitudinal passage 13 extending the length of the head. The head is further divided into a plurality of transversely extending chambers, the alternate chambers communicating with the passages 11 and 13 respectively. As shown in Fig. 4, the chambers 14 are in direct communication with passage 11 and the chambers 15 are shown communicating with passage 13. Liquid enters the inlet 10 and

passes immediately into passage 11 and the chambers in communication therewith, from whence it rises through the tubes which open into these chambers. After ascending the length of these tubes the liquid is directed 70 downwardly by means of the U-shaped caps 8 and descends through the tubes into outlet chambers 15. In this construction the liquid passes up and down the length of the shell once, thus giving a two-pass cooler.

75 A cooler of a greater number of passes may readily be obtained by merely altering the construction of the water head 9. Such a modified construction is illustrated in Figs. 9 and 10 in which the water head is so constructed as to produce a ten-pass cooler. The inlet 10 and outlet 12 may be located at the same end of the water head or they may be positioned as shown at the opposite ends of the head. Liquid enters the inlet 10 and is 80 then admitted to the passage 11 and chambers 14. From the chambers 14 the liquid rises in the tubes which open into these chambers and, after traversing the length of the shell, is directed downwardly through 85 the adjacent tubes of the elements by means of the caps 8. The first two transverse rows of tubes discharge into chambers 15, and the last row opens into a double chamber 31, 90 passage 13^a serving to interconnect the various chambers. Thus the total quantity of liquid admitted to the cooler passes up and down the height of the shell once and discharges into chamber 31. This portion of 95 the apparatus is in effect a two-pass cooler similar to the two-pass unit above described.

100 The chamber 31 is double the size of the chambers 14 and 15 and two transverse rows of tubes open into it. The liquid discharged into this chamber is thus free to ascend in the second of these transverse rows of tubes and also to enter the passage 11^a, from whence it passes into chambers 14^a and ascends the tubes which are in communication therewith. The liquid then makes its way 105 downwardly into chambers 15^a and a second double chamber 31^a. When it reaches the chamber 31^a the entire quantity of liquid has traversed the length of the shell four times, and the apparatus thus far constitutes a 110 four-pass cooler consisting of two double pass units. As many of these double pass units as desired may be incorporated into a single apparatus, thus affording as many passes as is desirable for any particular installation. The apparatus illustrated in Figs. 9 and 10 is a ten pass cooler comprising five of these units, the last unit discharging its entire flow into passage 13 and 115 from thence to the outlet 12.

120 Around the periphery of the head there is formed a flange 16 adapted to fit against the tube sheet 7 and form a fluid tight joint. The chamber walls are flush with the face of flange 16 and fit tightly against tube 125 130

sheet 7. If desired, packing may be provided between the contacting surfaces to insure fluid tight joints between chambers and to prevent leakage to the outside of the shell.

5 Tubes 6 are arranged in transverse rows in the tube sheet 7 and are positioned, as is shown in Fig. 1, so that one of the two tubes constituting any of the fluid conveying elements communicates with a chamber 14 and 10 the other with a chamber 15.

The top of the shell is fitted with a removable cover 17 clamped upon flange 2^a, packing being provided if desired between the contacting surfaces of the flange and 15 cover to form an air tight joint. The removal of the cover 17 gives ready access to all the tubes of the heat transferring element. To replace a damaged tube it is merely necessary to remove this cover and 20 the header, loosen the tubes of the damaged element from the tube sheet 7, and withdraw the damaged element through the top of the shell, a new element then being installed. A damaged heating element may 25 thus be replaced without disturbing any of the other heating elements even though finned tubes are used.

Each of the tubes is provided with an 30 external metallic rib or fin 18, as best shown in Fig. 6. This rib is preferably in the form of a spiral extending substantially the entire length of the tube and may be formed integrally with the tube or may be made of sheet metal and attached in any suitable 35 manner. If desired, a series of concentric ribs positioned one above the other may be employed instead of a single spiral rib. Heat is readily conducted from the fluid without the tube through the rib 18 into the 40 tube shell and thence to the cooling fluid flowing within the tube; or vice versa. Thus the heat transferring surface is greatly increased and more completely distributed throughout the area of the air passage. 45 Furthermore, especially with the spiral rib, a greater agitation is produced in the passing stream and the entire volume of air is thus brought more directly into contact with the heat transferring surfaces.

50 The air cooler is connected directly in a closed circuit with the apparatus to be cooled by the air, the air conduit being of an area substantially equal to the openings 3 and 4 in the cooler walls. An air stream of large 55 volume enters the cooler at the inlet 3, passes through the apparatus in a direction transverse to the cooling tubes, and issues at the outlet 4. Working fluid is admitted at the inlet 10 to passage 11, from whence it flows 60 into and fills all of the chambers 14. From these chambers 14 the fluid is forced into the communicating tubes and flows through them to the upper end of the shell, is reversed in flowing through the cap members 65 8, and returns to the lower end of the shell,

as indicated by the arrows on Fig. 1. The discharge from the tubes is received in the chambers 15, from whence it is conveyed into passage 13 and from thence discharged at 70 the outlet 12.

In Fig. 7 there is shown a modified form of head or chamber for the working fluid. The tube sheet 7 supports the tubes and rests against flange 2 in the manner already described. Two open rectangular rims 18^a 75 and 19 of channel cross-section are arranged around the periphery of the shell, a second tube sheet 20 being inserted between them, thus forming two separate chambers,—an inlet chamber 21 and an outlet chamber 22, 80 the latter being closed by a removable plate 24 clamped to the lower flange of rim 19. One of the tubes of each fluid containing element opens into chamber 21 and the other 85 is connected by means of pipes 23 to the outlet chamber 22, watertight joints being provided between the chambers. Pipes 23 may be cast integrally with tube sheet 7 or may be attached by means of a screw connection. If desired, these pipes may be eliminated by 90 having one of the tubes of each fluid conveying element of sufficient length to extend through the chamber 21 and communicate with the chamber 22, water-tight joints 95 being provided at the intersections with the tube sheet.

Fig. 8 shows a further modified form of head for use in installations where it is desired to have a multi-pass arrangement for the working fluid. This head consists 100 of a metallic casing 26 provided with a flange 27 adapted to fit against the tube sheet 7, and a lower flange 28 against which is fastened a bottom cover 24. A horizontal partition 29 is provided, the space below 105 which forms an outlet chamber 22 and the space above which is divided into a plurality of compartments 30 connected in series by means of the fluid conveying elements. Working fluid is admitted to one of the compartments 30 being then forced up one of the tubes of one row of the fluid conveying elements, through the cap 8, and back 110 through the other tube of the elements into the next succeeding chamber 30, which is in communication with the inlet tube of the next row of fluid conveying elements, the path of flow being indicated by the arrows, in Fig. 8. The working fluid proceeds 115 through the chambers and tubes in series until it enters the last chamber 30 which is provided with outlet opening 31 through which the fluid is discharged to the outlet chamber 22.

With the construction of the tube elements as shown in Fig. 1 in which these upper ends are left unsupported, vibration of the individual elements is apt to occur when the working fluid is pumped through them. To render the body of tubes stable 125 130

- and to prevent movement of the elements relative to each other, a metal sheet 32 of area approximately equal to the cross section of the shell is positioned to rest upon the tops of the various elements see Figure 10. Each of the caps 8 of the tube elements is formed with an upwardly extending prong 33 adapted to fit within a corresponding perforation in the sheet 32.
- 5 Any desired number of these prongs may be threaded to receive a nut 34 for the purpose of holding the metal sheet in firm contact with the tops of the tube elements. The various elements are thus spaced rigidly from each other and the construction renders the entire bundle of tubes rigid.
- 10 I have found that an apparatus embodying my invention possesses great flexibility in the matter of design and is readily adapted to meet the conditions of any installation. It is well recognized in the art that a high velocity of air is necessary for efficient heat transfer, since conduction through the volume of the air occurs but slowly
- 15 and the entire volume of air must be brought into intimate contact with the heat transferring surfaces. A high velocity affords a greater agitation of the gas particles and is otherwise conducive to proper heat transfer and high over all efficiency of the apparatus. Assuming a fixed height of air passage, the width of a heat transferring apparatus of this general type determines, however, the velocity of the air passed through
- 20 the cooler. The velocity of the water through the tubes depends upon the number of tubes in each pass. Consequently in an apparatus of the ordinary type the number of tubes per pass necessary to convey an amount of water through the cooler sufficient to adequately absorb the heat from the air often fixes the width of the apparatus at a value so great that the air velocity drops far below that which would
- 25 make for highest efficiency.
- 25 By employing a number of banks of tubes in parallel in each pass the width of the apparatus may be reduced to any desired dimension without decreasing the number of tubes in each pass. As a result, the normal quantity of cooling water may be passed through the apparatus at the most desirable velocity very much greater than that which would otherwise be obtained.
- 30 This flexibility of design makes it possible to build an apparatus to meet the requirements of any particular installation which will operate at a high efficiency and be of minimum weight and volume. I have found that in some installations it is possible to use a cooler embodying my invention which has a weight only about one half that of a cooler of the ordinary type designed for the same installation, and in which a small number of passes may be efficiently em-

ployed. The reduction in volume and weight of the apparatus results in a material reduction of costs.

While I have illustrated and described my invention as particularly applied to an air cooler, it is to be understood that my improved apparatus is applicable to any gas heater or cooler with advantage. The apparatus may also be used with the gas as the working fluid. If desired, continuous tubes of an inverted U-shape may be used instead of straight tubes connected by the cap 8, the type of construction illustrated being preferably, however, due to greater convenience in manufacture. The details of construction may be varied within the full scope of the appended claims.

I claim:

1. An apparatus of the class described having a containing shell, a gas passage through the shell, and a fluid passage in heat-exchanging relation therewith comprising, tubular elements arranged in a plurality of transverse rows, each element including a pair of tubes interconnected at one end and open at the other, and means for connecting the elements of each of said transverse rows in parallel and connecting the elements of different transverse rows in parallel whereby the width of the gas passage is not fixed by the number of elements in parallel.

2. In an apparatus of the class described having a containing shell, a gas passage through the shell, and a fluid passage in heat-exchanging relation therewith and comprising, a plurality of tubular elements each including a pair of tubes interconnected at one end and open at the other, a head for receiving the open ends of said tubes, said head being provided with transverse passages for connecting individual transverse rows of tubes, and with longitudinal passages for connecting said transverse passages so as to place transverse rows of said elements in parallel with other transverse rows of elements, and inlet and outlet passages for connecting with said longitudinal passages.

3. An apparatus of the class described having a containing shell, a gas passage through the shell, a fluid passage in heat-exchanging relation therewith comprising, a plurality of tubular elements, each including a pair of tubes interconnected at one end and open at the other, a head for receiving the open ends of said tubes, said head being provided with passages so connecting the tubes as to divide said elements into a plurality of groups, said groups being connected in series arrangement, and each of said groups comprising a plurality of rows of tube elements and also provided with other passages so arranged as to connect the individual elements of said groups

in parallel whereby the width of the gas passage is not fixed by the number of tubes in each group.

4. An apparatus of the class described having a containing shell, a gas passage through the shell, and a fluid passage in heat exchanging relation therewith comprising tubular elements arranged in a plurality of transverse rows, each element including a pair of tubes interconnected at one end and open at the other, and means for connecting the elements of each of said transverse rows in parallel and connecting the elements of different transverse rows in parallel, whereby the width of the gas passage is not fixed by the number of elements in parallel, and heat transferring elements of extended area provided on said tubes and lying in substantial parallelism with the direction of flow of the gas through the apparatus, whereby the gas is brought repeatedly into intimate contact with the heat transferring surfaces without substantial interference with the movement thereof.

5. In an apparatus of the class described having a containing shell, a gas passage through the shell, and a fluid passage in heat-exchanging relation therewith and comprising a plurality of tubular elements each including a pair of tubes interconnected at one end and open at the other, a head for receiving the open ends of said tubes, said head being provided with transverse passages for communicating with individual rows of tubes and with longitudinal passages connecting alternate transverse passages to place alternate rows of said elements in parallel, and inlet and outlet passages connecting with said longitudinal pas-

40 sages.

6. An apparatus of the class described having a containing shell, a gas passage through the shell, and a fluid passage in heat-exchanging relation therewith comprising a plurality of tubular elements each including a pair of tubes interconnected at one end and open at the other, a head for receiving the open ends of said tubes, said head being provided with transverse passages for placing the individual tubes connected therewith in parallel, and longitudinal passages arranged to interconnect the transverse passages in such manner that alternate transverse rows of said tubular elements are connected in parallel relation, and inlet and outlet passages connecting with said longitudinal passages.

7. In an apparatus of the class described,

the combination of a casing having two opposite sides open throughout substantially their entire area for connection to a gas passage, a tube sheet forming a third side to said heater, tubes set in said tube sheets and extending across said gas passage, said tubes being arranged in pairs with the free ends of the tubes of each pair connected, a removable wall forming the side of said casing opposite said tube sheet and a header attached to the outer face of said tube sheet said header having partitions lying between the ends of the tubes of each pair and forming inlet and outlet passages therefor, said header also having inlet and outlet manifolds connecting said inlet passages and outlet passages respectively.

8. In an apparatus of the class described, the combination of a casing having two opposite sides open throughout substantially their entire area for connection to a gas passage, a tube sheet forming a third side to said heater, tubes set in said tube sheets and extending across said gas passage, said tubes being arranged in pairs with the free ends of the tubes of each pair connected, a removable wall forming the side of said casing opposite said tube sheet and a header attached to the outer face of said tube sheet said header having partitions extending transversely of said gas passage and lying between the ends of the tubes of each pair and forming inlet and outlet passages therefor, said header also having inlet and outlet manifolds extending longitudinally of said gas passage and connecting said inlet passages and outlet passages respectively.

9. An apparatus of the class described having a containing shell, a gas passage through the shell and a fluid passage in heat exchanging relation therewith, comprising a plurality of tubular elements, each including a pair of tubes interconnected at their outer ends, a supporting plate at the outer ends of the said tubular elements, substantially co-extensive with the bank of tubes constituting the fluid passage, said plate having a series of holes spaced to correspond to the location of the respective tube elements, and a projecting portion at the interconnected end of each of said tubular elements adapted to enter the hole corresponding to that element, thereby supporting said elements as a rigid unitary body and locating each element with respect to the other elements of the apparatus.

In testimony whereof I affix my signature.
JOSEPH PRICE.
